(57) **CLAIM**

The ornamental design for a reusable gift wrap, as shown and described.

DESCRIPTION

FIG. 1 is a top front perspective view of a reusable gift wrap in an unoccupied configuration showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top front perspective view of the reusable gift wrap in an occupied configuration which also shows my new design;

FIG. 9 is a front elevational view of the occupied configuration of my new design shown in FIG. 8.

FIG. 10 is a rear elevational view of the occupied configuration of my new design shown in FIG. 8.

FIG. 11 is a right side elevational view of the occupied configuration of my new design shown in FIG. 8;

FIG. 12 is a left side elevational view of the occupied configuration of my new design shown in FIG. 8;

FIG. 13 is a top plan view of the occupied configuration of my new design shown in FIG. 8; and,

FIG. 14 is a bottom plan view of the occupied configuration of my new design shown in FIG. 8.

The portions in FIGS. 1-14 shaded by stippling represent contrast in color, texture and/or material, which constitutes a part of the design.
